FIREPROOF BUILDING BLOCK TILE

Charles B. Spicer, Brooklyn, N. Y.

Application July 29, 1932, Serial No. 625,625

3 Claims. (Cl. 72—16)

My invention relates to building block tile for buildings or other structural units and has for its main object to provide fireproof building block tile which may be quickly and easily secured to the framing of structure in interlocked relation, by anyone handy with tools, without employing the use of cement or mortar as a bond, or the services of a skilled mason or bricklayer.

A further object of the invention is to provide a building block tile which when secured to the framing of the structure, so encases the framing members as to make the structure, the framing and members thereof fireproof.

A still further object of the invention is to provide a building block tile which may have the surface which is exposed to the elements, herein-after called the outer surface, formed decoratively or to take stucco, or other facing material, and the inner surface formed to take plaster or plaster board.

A further object of the invention is to provide a building block tile which may be so fastened or connected with the framing of the structure as to practically form an integral part therewith.

These and various other objects and advantages will be readily understood from the following description and accompanying drawing, but it will be noted that certain modifications may be made without departing from the scope of the invention.

In order that my invention shall be thoroughly understood I shall refer to the several illustrations of the accompanying drawing in the following description. In said drawing I have shown one form of the construction of the invention, but it is understood that I do not wish to limit myself to such form since the invention, as expressed in the claims, may be embodied in a plurality of forms.

Fig. 1 represents a sectional plan view of walls constructed with building tile of my invention,

Fig. 2 is a perspective front view of the building block tile secured to the framing,

Fig. 3 is a top plan view of the tile,

Fig. 4 is a side view of the building block tile,

Fig. 5 is an enlarged, fragmentary view of part of the building block tile.

Figs. 4 and 5 are drawn to a larger scale than other views.

Figs. 1 and 2 show part of the frame structure 10 of a building to which my block tiles 11, are secured. The blocks may be made of any fireproof material, preferably rectangular in shape, and of a length which equals the distance between two or more of the studs, joists, or rafters 10 of a building. They have hollow ducts 12, to reduce

the weight of the block and permit the circulation of air. The ducts also act as heat and sound insulators. Each of the block tiles have flanges 13 and 14 at each end, as well as an intermediate flange or wall 15. The ducts 12 are located in rearwardly extending parts 16, which fill in the space between the joists 10, and which are made of a depth equivalent to the width of the joists or metal framing when such is used.

The block tiles are secured to the framing by 10 fastening means such, for example, as nails 17. These nails are inserted in counterbored or slotted holes 18. After the block tile has been nailed in place the counterbored recesses are filled with a suitable protective material which covers and 15 protects the nail heads.

The flanges of the block tiles used at corners of a building are preferably chamfered as shown at 19. To prevent breakage from shock the flanges and wall section 15 may be reenforced 20 with metal if desired. I also prefer to provide the tiles with means such as the customary tongue 20 and groove 21, so as to make a weather tight joint between them. The tiles are preferably fastened to the structure in staggered position. As shown in Fig. 2 the tile may be ornamented with any suitable face in imitation of 25 bricks, cement blocks, granite or other desired design. On the other hand, the outer face of the block tile may be formed so that a coat of stucco or other facing material will more readily 30 adhere to it. The inner faces of the block tile are preferably roughened as shown in Fig. 5, so that they will more readily hold a coating of plaster as indicated 23.

While I have illustrated the block secured to a wood frame structure, it is evident that metal framing may be covered or encased as readily, by substituting screws, bolts, or rivets as the fastening means.

It will readily be seen that this tile provides a building material very readily placeable; that they lend themselves to many attractive ornamental schemes and with their use a heavy frame structure is not required, since they will support themselves in interlocked relationship, thereby strengthening a structure. It will also be seen that, inasmuch as the framing of the structure is encased and covered by the tile and the inside plaster, the structure is to a great extent 45 protected against fire. The use of sheathing, 50 tar paper, lathe, furring strips, etc., may be dispensed with as may be the services of a skilled bricklayer or mason.

Having described my invention, what I claim as new and wish to protect by Letters Patent is:

1. A building block comprising a block having a rearward extension adapted to fill the space between the framing members of a structure; said extension having a depth equal to the width 5 of said framing members, so that the block may be inserted horizontally in a structure without altering or adding to the framing members and so as to form a continuous surface with the inner surfaces of the framing members; the front face 10 of the block extended sidewardly to form flanges at both ends of the block; said flanges being of such sizes as to form a space between any two adjoining blocks substantially equal to the thickness of a framing member; and means provided 15 in said flanges for receiving fastening means for securing the block to the structure.
2. A building block comprising a block having a rearward extension adapted to fill the space between the framing members of a structure; 20 said extension having a depth equal to the width of said framing members, so that the block may be inserted horizontally in a structure without altering or adding to the framing members and so as to form a continuous surface with the inner surfaces of the framing members; vertical ducts formed in said extension; the front face of the 25 block extended sidewardly to form flanges at
- both ends of the block; said flanges being of such sizes as to form a space between any two adjoining blocks substantially equal to the thickness of a framing member; and means provided in said flanges for receiving fastening means for securing the block to the structure. 5
3. A building block comprising a block having a rearward extension adapted to fill the space between the framing members of a structure; said extension having a depth equal to the width 10 of said framing members, so that the block may be inserted horizontally in a structure without altering or adding to the framing members and so as to form a continuous surface with the inner surfaces of the framing members; vertical ducts 15 formed in said extension; the front face of the block extended sidewardly to form flanges at both ends of the block; said flanges being of such sizes as to form a space between any two adjoining blocks substantially equal to the thickness 20 of a framing member; and means provided in said flanges for receiving fastening means for securing the block to the structure; and means provided adjacent to the front face of the block for forming interlocking joints between adjoining blocks. 25

CHARLES B. SPICER.
